HAND LOOM

Frank Havice, New York, N. Y.

Application November 1, 1945, Serial No. 626,063

7 Claims. (Cl. 139—29)

1

This invention relates to hand looms for weaving a wide variety of fabrics, and more particularly to a hand loom which is portable and suitable for home use.

Prior home looms have consumed considerable space in the household and cannot be easily stored within an adjoining, usually limited, closet space of a room. Also, such looms ordinarily bristle with projections with which one moving about the loom may be easily caught or entangled and which, though submitted to little force, become easily broken. Furthermore, the hand looms of the horizontal type may, during certain operations, require the services of two people, one stationed at one end of the machine adjacent to the warp roller and another stationed at the opposite end of the machine adjacent to the cloth roller. In the horizontal machine considerable reaching is necessary from one end of the machine in order to reach the work and to put the shuttle through the established shed between warp strands. This reaching becomes tiresome and reduces the volume of work which the operator can do in a given time.

Prior machines of the upright type have similar disadvantages as above mentioned. They have generally been of a type which stood on the floor, consuming considerable space and making it necessary for the operator to stand up to the same as he must do with the horizontal type machines in order to be able to easily throw the shuttle through the prepared shed of warp strands. None of the machines, either of the horizontal or upright type have been sufficiently compact so that the operator may sit in a chair and be in easy reach of all of the operating parts of the machine.

It is accordingly the principal object of the present invention to provide a hand loom for weaving a wide variety of fabrics, which is compact, simple in construction, truly portable and adapted to be carried as a suitcase is carried, easily stored, and when disposed in place on a table or piano bench is of such height that the operator may be seated in a chair and have a full control of all of the operating parts of the loom.

It is another object of the invention to provide in a portable loom a beater frame which will lie parallel to and close to the heddle frames when not in use, whereby to provide maximum shed

2

between warp strands and as well a beater frame which is automatically returned to this position when it is released from its lowered or working position.

It is another object of the invention to provide in a loom suitable guiding means or mechanism adapted to be inserted into the shed to guard against the falling of the shuttle at any point in the extent of its passage through the shed, and wherein the guiding means is automatically removed from the shed as the beater frame is brought down into position to beat the weft or woof threads into the cloth.

It is another object of the invention to provide means to prevent pushing the shuttle accidentally through the warp strands forming one side of the shed which may otherwise occur while inserting the shuttle into the shed.

It is still another object of the invention to provide a hand loom adapted for home use which is free of projecting portions, streamline in design, wherein the operating parts are fully enclosed within a supporting and protecting frame and not vulnerable to breakage and further wherein the loom may consume only little space in a storage closet so that a number of them can be readily stacked or disposed close to each other for storage while not in use.

It is another object of the invention to provide an arrangement of the heddle frames which is compact, readily accessible and easily selected by hand from a point immediately in front of the operator and arranged to consume minimum space within the loom frame.

According to the invention, the loom frame is of streamline design including generally side wall pieces with transverse spacing members disposed therebetween. At the top of the frame is located the warp roller and warp beam and at the bottom is located the cloth roller and cloth beam. Warp strands leave the warp roller and are guided downwardly from the warp beam through a set of heddle frames and over the cloth beam to the cloth roller. A beater frame containing a reed is pivoted on a bar at the rear of the loom frame and between the end frame members and is adapted to lie parallel to and close to the heddle frames while the shuttle is being passed from one side of the warp shed to the other. A spring automatically maintains the beater frame in this

position when not in use and after the operator has used the beater frame to pack the woof threads into the apex of the shed against the action of this spring and released it. By the use of this return spring one stroke of the operator's arm is eliminated. The hand need not be moved to return the beater but may move directly to the heddle frames or to the point where the shuttle has fallen to effect the next operation.

Coupled to this beater frame is a backboard arrangement adapted to be automatically projected into the shed as the beater frame is raised so as to provide a catch for the shuttle as it is passed through the shed to prevent the shuttle from dropping into the narrow converging space between warp strands to become entangled therewith.

All of the operating parts lie within the confines of the supporting frame. The frame end pieces have holes in them to contain hand wheel parts for operating the warp roller and the cloth roller so that these parts need not project beyond the outside faces of the same, thereby preventing them from becoming easily broken by passing objects and permit them to be stored in flush end to end relation with each other without consuming additional space beyond the confines of the frame. The top of the loom likewise is flat and has no projections extending therefrom so that one loom can be supported on top of another loom or other objects in the closet where the loom is stored may be disposed on top of it. At the rear of the frame, there are no projections. At the front of the loom there are projections only when the loom is in use and the heddle frames are withdrawn. Even with the heddle frames withdrawn, the warp threads are never brought outwardly of the confines of the frame so as to be without protection. In order that the shuttle can be easily inserted from one side of the loom and thrown to the other side, the frame end pieces are cut out to provide access to the shed. These cutout openings not only permit the throwing of the shuttle but render the operating dials for the rollers located in the end pieces of the frame more accessible.

For other objects and for a better understanding of the invention, reference may be had to the following detailed description taken in connection with the accompanying drawing in which

Fig. 1 is a vertical sectional view of the loom showing the beater frame in both its raised and lowered positions;

Fig. 2 is a detailed sectional view of the detent mechanism associated with each of the heddle frames;

Fig. 3 is an end elevational view showing the operating dials for the warp and cloth rollers;

Fig. 4 is a front elevational view of the loom looking in a direction parallel to the heddle frames;

Fig. 5 is a fragmentary side view showing how far the beater frame moves to cause the shuttle guiding means to move clear of the shed formed by the warp threads;

Fig. 6 shows how far the cloth may build up before it interferes with the shuttle guiding means. It also shows how the backing board of the shuttle guiding means accommodates itself to the threads forming the rear portion of the shed;

Fig. 7 is a horizontal cross-sectional view through loom taken on the line 7-7 of Fig. 1 and looking in plan upon the backing board;

Fig. 8 is an enlarged fragmentary view of the

backing board showing the connection of the fingers therewith.

Referring now particularly to Figs. 1, 3 and 4, there is shown a loom frame 11, comprising end pieces 12 and 13 and pairs of top and bottom transverse spacing members 14 and 15 for connecting the end pieces together. The end pieces 12, 13 are wide at their bottoms and narrow at their tops. The transverse members 14 at the top are spaced from one another, from front to rear, more closely than the transverse members 15 at the bottom.

On the bottoms of the end pieces 12 and 13 and at opposite edges thereof are supporting buttons or feet 16, preferably of resilient material, for supporting frame 11, on a table or piano bench without inflicting scratch marks upon the same. Should it be desired to stack the frames or the completed looms on top of each other, the same may be readily done by virtue of the top spacing members 14 being more narrowly spaced than the bottom spacing members 15 and without the buttons 16 interfering or engaging any portion of the upper part of the lower loom frame. At the bottom of the end pieces 12 and 13 there is relieved opening 17, which serves to lighten the frame. On stacking, support is had by the spacing members 15 of the upper frame upon the spacing member 14 of the lower frame. Also, the bottom edges of the end pieces 12 and 13 of the upper frame will receive support from top edges of the lower frame as the one frame is stacked thereon. If it is desired to carry the frame as a suitcase would be carried, the person may grasp one of the top spacing members 14, intermediate the length of the same so as to afford suitable balance of the loom within the hand and walk away with it.

In one of the top spacing members 14 is a slot 20 adapted to receive a thread guide. This guide is fitted in the slot at the time the strands are supplied to the warp roller in order to have them properly aligned on the roller.

Pivoted in the frame 11, near the top thereof and close to the rear of the frame is a transversely extending warp roller 21. The pivotal connection of this roller 21 is made at each end with the inside walls of the end pieces 12, 13, by means of a cross-plate 22, diametrically disposed across an opening 23 adapted to house a dial or hand wheel 24 on end shaft 25 of the roller, Fig. 3. The roller 21 itself is made of wood and end shaft 25 embedded in respective opposite ends of the same. The hand wheel arrangement just described is provided at both ends of the roller so that the roller can be turned from either end of the loom. On the end piece 13 and in order to prevent free rotation of the roller in one direction, there is provided a ratchet arm or detent 26, Fig. 3 pivoted at 26a. As the roller is turned with the ratchet arm 26 in place on a ratchet wheel 27, rigid with the roller, warp strands 28 spaced along the extent of the roller will be tightened.

Extending flush with the inner wall face of the end piece 13, and adapted to slide over pins 29, in the end piece, Fig. 3, is a slide 31, having an inwardly turned handle portion 32 readily accessible to the operator in front of the loom, for unlocking the arm 26 from the ratchet wheel 27, so as to free the warp roller 21 in both directions of rotation. On the warp roller 21 are spacing pins 33 for maintaining groups of the warp strands 28 spaced throughout the length of the roller.

Near the bottom of the frame 11 and substantially vertically aligned with the roller 21, is a

cloth roller 34 for collecting the accumulated woven cloth. This roller 34 is also made of wood and is connected to the end pieces 12, 13 by means of bearing plate pieces 35 extending across openings 36 which house cloth roller hand operating dial or wheels 37.

Each dial wheel 37 is secured to a hollow shaft 37a extending through the bearing plate 35 to the roller 34. Each hollow shaft 37a is shown provided with a transverse pin 37' positioned near an end of the shaft. Each pin 37' is adapted to engage a removable crank (not shown) or similar device for the purpose of rapidly rotating shaft 37a or for applying a greater torque thereto than can be applied conveniently by any of the dial wheels 37. A ratchet arm or detent 38 pivoted at 38' to the frame end piece 13 is adapted to be unlocked from a ratchet wheel 39 on cloth roller 34 by a slide 39', Fig. 3, carried on pins 40 projecting from the inner wall face of the end piece 13. The slide 39' extends sufficiently forward toward the front of the frame so as to be readily accessible to the operator. This slide likewise has an inwardly extending handle projection 41. This ratchet mechanism is such that when in operation it ratchets in a reverse direction from the ratchet mechanism on the warp roller 21. This is so that one ratchet mechanism will be provided in the system to keep the cloth and warp strands tight while the rollers are being rotated. If the warp roller is turned to return or tighten the warp strands the ratchet mechanism on the cloth roller locks the cloth roller. If the object is to advance the cloth on the cloth roller, the ratchet mechanism on the work roller is released, and the cloth roller is turned. With both ratchet mechanisms engaged with their respective rollers, both rollers are locked to retain the cloth and warp strands tight between warp and cloth beams 42 and 43, located respectively at the top and bottom of the frame and over which the warp strands and cloth ride. The warp beam 42 is located substantially centrally of the frame, and close to the warp roller 21, whereas the cloth beam 43 is located close to the front of the frame and somewhat removed from the cloth roller 34. The cloth beam 43 is not directly under the warp beam 42. This not only affords space for locating the cloth roller 34 on the frame above the cloth beam 43 and keeping the frame depth within minimum dimensions, but places the warp strands in a slightly inclined position relative to the vertical and such that the operator would look upon them in the same manner as he would look upon a book, thereby permitting the operator to stand or sit up straight to work at the loom.

It should now be apparent that by having the operating dials 24 and 37 confined within large openings 23 and 36 in the end pieces, that the operator is not only given ready access to these dial members but projections are eliminated from the loom and the looms themselves can be placed in end to end relation or against a wall without consuming unnecessary storage space. Furthermore, the parts are protected against outside interference which might disconnect them or loosen them from the frame. Also, the dials for the rollers are at both sides of the loom so that they may be operated by right-handed and left-handed persons or operation with right or left hand at will.

Fastened on the inside of the end pieces 12 and 13 and extending therebetween is a heddle frame arrangement 45 including a plurality of heddle frames 46, 47, 48 and 49. Each of these heddle frames have a plurality of loose and laterally-

adjustable heddle wires 51 with the usual eye portions 52 through which the individual warp strands 28 extend, Fig. 1. These frames are rectangular and are made of rigid construction and their ends are respectively slidably contained in channels 53, Figs. 2 and 4, fastened to board or plates 54 which are in turn connected to the inner faces of the end pieces 12, 13.

In the ends of each frame are grooves 55 in 10 each of which ride a spring-biased detent ball 56 housed with its operating spring 57 in a little container 58. The ball assembly is inserted as a unit through a hole in the channel and into a recess 59 provided in the plate 54. At the ends of the grooves 55, are enlarged round ball-retaining recesses 60 in which the ball is pressed to arrest the frames in either their in and out positions. These detents thus limit the movement of the frame. The rearward movement of the frames may further be arrested by a rubber stop strip 60' at the rear of the frame, Fig. 1. The heddle frames have handles 61, 28', 63 and 64 for withdrawing the heddle frames to form a shed opening 62 between warp strands 28 and beneath the heddle frames. The handle 61 of the top frame 46 is aligned with the handle 64 of the bottom heddle frame 49 but handles 62 and 63 are offset on their respective frames 47 and 48 to the left and right with respect to the handles 61 and 65. This is purposely done so that the operator will have free access to the handles and can readily grasp one of the same without grasping the other. Each of these handles can have indicia thereon to assist in their selection for operation according to the design in the tapestry or carpet being made. Fingertip control of the heddle frames is thus had.

On the rear of the loom frame is a rod 66 which serves as a pivot for a beater frame 67, Figs. 1 and 4. Each end of the rod is fastened to the end pieces 12, 13 by a pair of cooperating lock nuts 68 and 69. Each lock nut 68 is confined within a large recess 70 and can be loosened by a socket wrench. No part of the nut 68 or of the rod 66 extends outwardly of the outside wall of the end piece. By this arrangement the two end pieces 12 and 13 may be drawn together slightly or pushed outwardly to properly adjust the channels 53 to the edges of the heddle frames 46-49. The beater frame 67 has L-shaped attaching plates 71 each having an opening 72 through which the rod 66 extends. The beater frame is retained against lateral displacement on the rod 66 at the ends thereof by a washer 73 and pin 73a. Should it be desired to move the beater frame laterally a slight amount to more properly align slots 74, formed between guide wires 74a, with the warp strands, the lock nuts 68 and 69 are loosened and the rod 66 bodily adjusted this slight amount. With the adjustment of the rod 66, the beater frame 67 will be adjusted along with it.

By having the depending plates 71 on the beater frame so as to lower or downwardly offset the pivot point of the beater, the beater frame 67 when raised may be brought parallel to and close to the bottom heddle frame 49, whereby to give maximum shed height between the separated warp strands.

The beater frame 67 is raised and held in its raised position by one or more return springs 76, Figs. 1 and 4, connected through an adjustable connection 77 with the end pieces 12, 13. The connection of each spring 76 with the beater frame is through a point 78 on the plate 71. The

front edge of the beater frame is cut away at 79 so as to permit the same to be easily grasped by the operator and to thus form a handle formation 80 on the beater frame, Fig. 4.

In order that the beater frame will not be brought up against the bottom heddle frame, there are provided stop bars 81, 82 at opposite sides of the frame which will bear against the lower edges of boards 54 which connect the heddle frame arrangement 45 to the inner walls of the end pieces 12 and 13.

With one or more of the heddle frames withdrawn, as shown in Fig. 1, the warp strands are separated and the shed space 62 is formed. By keeping the beater frame 67 up and out of the way, a maximum size shed space 28' is afforded. A shuttle 83, Fig. 3, can be readily thrown through this space without being interfered with by the beater frame 67. Once one or more woof or horizontal threads are fed between the warp strands, the beater frame 67 is brought down to a dot-and-dash line position 85, Fig. 1, taking with it the woof threads and adding them to a cloth piece 86 extending around the cloth beam 43 and toward the cloth roller 33. When the beater frame 67 is released by the operator when in the lowered position, it is returned to its raised position by the force of springs 76. The operator, therefore, need not exert force to return the frame to its upper position, although his hand will ride up with the frame.

The warp threads may be fastened to the warp roller by pivoted loops 87 secured to the surface of the roller, Fig. 1. The advancing ends of the warp threads are secured to the cloth roller 34 by rod 88 secured between straps 88' each fastened by a tack 88" to the roller surface.

In order to keep the loom frame of minimum depth and width, the end pieces are cut away as indicated at 89 so that the shuttle can be readily passed into the end of the shed 28'. This cut 89 extends sufficiently rearwardly into the end pieces so as to be rearwardly of the shed and its rear edge 89', being inclined rearwardly and parallel to the warp strands 28 as they extend between the beams 42 and 43. These cut outs not only provide clearance at the ends of the shed for the insertion of the shuttle 83 but make possible a short path of the hand from the shuttle inserting position to the handle 80 of the beater frame 67.

Referring now to Figs. 5, 6, 7 and 8 there is shown more in detail my mechanism for preventing the shuttle from dropping into the bottom of the shed and for preventing entanglement of the forward end of the shuttle with the warp strands. This mechanism includes a backing board 91 having forwardly projecting fingers 92 connected to its lower end and adapted to project between the strands and through the shed when the beater frame is raised. It will be noted that the backing board 91 lies flush with rear strands to support them against rearward displacement should the shuttle 83 be carelessly inserted by the operator with the end between these rear strands. The shuttle upon striking the backing board will be prevented from passing between the strands forming the rear of the shed and will tend to fall to the bottom of the shed and come to a point of rest. It will, however, be prevented from reaching the bottom of the shed by the forwardly projecting guide fingers 92.

When the beater frame is lowered or pushed downwardly against the action of the spring 76 to beat the woof threads into the cloth piece 86,

the backing mechanism is automatically pivoted, Figs. 1 and 5, about its hinge point 93 on the beater frame by a tension spring 94 connected at one end to the backing board mechanism at 95 and at its other end to the rearward portion of the beater frame as at 96. This rearward movement of the backing board mechanism is made possible by the release of a projection 97 of the backing board mechanism from the end board 54 of the heddle frame arrangement. This release is effected automatically as the beater frame is forced down and is completed when beater frame assumes the position shown in Fig. 5. This pivotal movement of the baffle mechanism relative to the beater frame continues until the fingers are out of the shed and the spring 94 has come to a center position between points 93 and 96, as shown in Fig. 5. It will stay in this on-center position as the beater frame moves to its lower position, Fig. 1 and until such time as the beater frame is returned to its raised position and forced downwardly out of its center position by engagement of the lug 97 with the heddle frame end board 54.

There are two of the mechanisms just described, one at each side of the frame and tied together through the transversely extending backing board 91. The mechanisms work in unison and the backing board is uniformly positioned against the rear warp strands.

In order that the backing board will be adaptable to substantially any inclination of the rear strands, the mechanism is made in two parts 101, 102, both pivoted at the point 93 on the beater frame and relatively movable with respect to each other. The ends of these two parts are connected together by a light spring 103, so as to tend to keep the two parts locked together. However, when the mechanism is up and the backing board 91 is flush with the rear strands as shown in Fig. 1, the parts 101 and 102 are drawn apart so as to properly align a backing board 91 with the rear strands. This alignment of the backing board 91 with the rear strands will continue to be had throughout the normal working range with which the cloth piece 86 is permitted to extend at any time above the cloth beam 43. However, with the cloth piece 86 permitted to be built up to a point as shown in Fig. 6, the arm 102 may have its pin 104 engage with a shoulder 105 on the arm 101 and the backing board 91 would lie at its top edge slightly away from the rear strands as indicated, but it will not do so to any great disadvantage. At this time the cloth piece should be rolled up on the cloth roll 34.

It will be understood that as the beater frame is moved down, the backing board mechanism moves as a unit rearwardly due to the action of spring 94 to a point removed from the shed and out of the way to permit the beating of the woof threads into the cloth piece. As the beater frame is released and raised by its spring 76 the backing mechanism is automatically projected into its operative position within the shed and against the rear strands.

Referring to Fig. 8 there is shown the detailed construction of the backing board 91 and its fingers 92. The fingers 92 are very narrow and are widely spaced apart, Fig. 7. The backing board 91 consists of a flat piece positioned on edge and rigidly secured to a depending portion 106 on the pivot arm 102. The rear ends of the fingers project through slots in the backing board and the projections on the back of the backing board are turned over as indicated at 107 and

secured to the backing board by a screw, rivet or other similar means 108.

I have described what I believe to be the best embodiments of my invention. I do not wish, however, to be confined to the embodiments shown, but what I desire to cover by Letters Patent is set forth in the appended claims.

I claim:

1. In a hand loom, an upright frame including end pieces, warp and cloth rollers and beams connected between the end pieces in vertically-spaced relation and adapted to support warp strands and cloth, a heddle frame arrangement connected to the frame between the warp and cloth beams and adapted to separate the warp strands to form a shed, said heddle frame arrangement when retracted being of such depth as to lie within the front and rear confines of the frame, a beater of substantially the same depth and lying within the same confines of the frame, offset plates on the rear of the beater and means for pivotally connecting the offset ends of the plates to the rear of frame, whereby said beater may lie parallel to and close to the heddle arrangement when out of use.

2. In a hand loom, an upright frame including end pieces, warp and cloth rollers and beams connected between the end pieces in vertically spaced relation and adapted to support warp strands and cloth, a heddle frame arrangement connected to the frame between the warp and cloth beams and adapted to separate the warp strands to form a shed, said cloth roller being positioned in the frame substantially in vertical alignment with rearward edge of the heddle frame arrangement, a beater frame of substantially the same depth as the heddle frame positioned between the heddle frame and the cloth roller and adapted to lie parallel to and close to the heddle frame in its out-of-use position, vertically offset extension means on the rear of the beater frame adapted to extend to a location near to and rearwardly of the cloth roller, and means for pivotally connecting the offset means to the upright frame, whereby to permit a full swing of the beater frame free of the roller and thus making for compactness of the loom.

3. In a hand loom, an upright frame including end pieces, warp and cloth rollers and beams connected between the end pieces in vertically spaced relation and adapted to support warp strands and cloth, a heddle arrangement connected to the frame between the warp and cloth beams, a beater frame adapted to normally lie in an out-of-use position parallel to and close to the heddle arrangement, means for pivotally connecting the rear end of the beater to the upright frame for vertical movement therein, said connecting means including a rod extending between the end pieces and adapted to be axially adjustable with respect thereto, means for securing the frame to the rod against lateral displacement thereon, and releasable means for locking the rod to the end pieces whereby the beater may at times be laterally adjusted with respect to the heddle arrangement and warp strands.

4. In a hand loom, an upright frame including end pieces, warp and cloth rollers and beams connected between the end pieces in vertically spaced relation and adapted to support warp strands and cloth, a heddle arrangement connected to the frame between the warp and cloth beams, a beater frame adapted to normally lie in an out-of-use position parallel to and close to the heddle arrangement, said end pieces having

small holes axially aligned with one another and at least one of the small holes having a counterbore opening extending inwardly of the outer face of the end piece, means for pivotally connecting the beater to the end pieces for vertical movement therein including a rod extending through the small holes and into a counterbore opening, lock nuts for preventing axial movement of the rod in the opening, one lock nut bearing against the inner face of the frame piece and the other lock nut contained within the counterbore opening, bearing against the bottom thereof, and without protruding from the outer face of the end piece, means for preventing lateral displacement of the beater on the rod, said rod thereby being axially adjustable in the end pieces upon the lock nuts being released.

5. An upright frame for looms comprising end pieces with narrow top edges and wide bottom edges transversely extending spacing members connected between the end pieces at their tops and bottom edges, said spacing members being symmetrically spaced and the top spacing members being more narrowly spaced than the bottom spacing members, said spacing members lying within the confines of the top and bottom edges, cushioning supports at the opposite ends of the bottom edges, sufficiently spaced to be free of the narrow top edges of the end pieces as the frames are stacked upon each other.

6. In a hand loom, an upright frame including end pieces, a warp roller and a beam connected between the end pieces near the top of the frame, a cloth roller and a beam connected between the end pieces near the bottom of the frame, warp strands extending between the rollers, a heddle frame arrangement connected to the end pieces intermediate the warp and cloth beams and disposed to displace the warp strands to form a shed, a beater frame pivotally connected to the end pieces for vertical movement to and from a position parallel to and close to the bottom of the heddle arrangement, tension spring means connected between the beater and the upright frame for automatically returning the beater to its raised position, a backboard carried by the beater frame and pivotally secured thereto and further spring means interconnecting the backboard and the beater frame and disposed to bring the backboard into yielding engagement with the shed when the beater frame is positioned close to the bottom of the heddle arrangement.

7. In a hand loom, an upright frame including end pieces, a warp roller and a beam connected between the end pieces near the top of the frame, a cloth roller and a beam connected between the end pieces near the bottom of the frame, warp strands extending between the rollers, a heddle frame arrangement connected to the end pieces intermediate the warp and cloth beams and disposed to displace the warp strands to form a shed, a beater frame pivotally connected to the end pieces for vertical movement to and from a position parallel to and close to the bottom of the heddle arrangement, tension spring means connected between the beater and the upright frame for automatically returning the beater to its raised position, a backboard carried by the beater frame and pivotally secured thereto, further spring means interconnecting the backboard and the beater frame and disposed to bring the backboard into yielding engagement with the shed when the beater frame is positioned close to the bottom of the heddle arrangement and a plurality of narrow members spaced along the back-

11

board and shaped to protrude into the shed when the backboard is in proximity thereto and shaped to provide support for the shuttle when the latter is within the shed.
